UNITED STATES PATENT OFFICE.

PETER J. McGOWAN AND RALPH J. DIKEMAN, OF NEW YORK, N. Y.

CAR-CONTROL SYSTEM.

1,183,995.

Specification of Letters Patent. Patented May 23, 1916.

Application filed December 2, 1914. Serial No. 875,203.

To all whom it may concern:

Be it known that we, PETER J. McGOWAN and RALPH J. DIKEMAN, citizens of the United States, and residents of New York, 5 borough of Brooklyn, county of Kings, and State of New York, and of New York, in the county of Bronx and State of New York, have invented certain new and useful Improvements in Car-Control Systems, of 10 which the following is a specification.

This invention relates to car control systems.

In electric street car systems in which the cars run singly, it often happens that a car 15 becomes disabled through failure of the motor or the burning out of the controller or some other point of the motor circuit. It becomes necessary, therefore, for the following car to push the disabled car from behind. This is dangerous because the motorman has to stand on the rear car and control the motor and brake in accordance with the signal of a person standing on the front platform of the disabled car. Often it is 20 necessary to stop the car quickly and the delay in the transmission of the signal is sufficient to cause an accident. Also it may happen that a car is disabled when going up a very steep grade, and it is necessary for 25 two cars to assist in shoving the disabled car up the hill. This hitherto has required two separate signals to the motorman on the two rear cars from the person on the front platform of the disabled car before the 30 train of cars can be stopped.

The present invention has for its primary 35 object to provide means whereby the motorman standing on the front platform of the disabled car may control the motor circuit of the rear car, so that the stopping and starting of both cars is controlled directly by the motorman standing on the front platform of the disabled car.

A further object is to provide means of 45 this character which can be used for controlling a number of cars running in train rearwardly of the disabled car.

A still further object is to provide means of this character which may be installed at 50 very low cost on existing types of cars.

The various further objects and advantages will more fully appear from the detailed description and the features of novelty will be particularly pointed out in the 55 claims.

In the drawing, the figure is a diagram of the improved control system shown as applied to two cars coupled together.

Referring in detail to the drawings, the disabled car 10 is shown as being driven in 60 the direction of the arrow from behind by the good car 11. In the ordinary cars now in use, the motorman would in this event stand upon the front platform 12 of the rear car 11 and would start and stop his car in 65 accordance with the signal of the conductor or other person standing on the front platform 13 of the disabled car 10. According to the present invention, however, the motorman standing on the front platform 13 70 of the disabled car directly controls the motor circuit of the rear car and also controls the operation of the brakes on his own car. The control of the motor circuit is obtained as follows:

In the motor circuit 14 which is normally controlled by the controllers 15 and 16 located on the front and rear platforms of the car, is a contactor 17. On many cars now in use, this contactor is already installed in 80 connection with the operation of the sliding doors by the motorman, and in such case, it could be utilized and our improved system applied thereto. This contactor consists of a plunger 18 actuated by a coil 19 connected 85 on one side by a wire 20 to a contact 21 on the controller and on the other side by a wire 22 to one of two parallel wires 23 and 24 running the length of the car. We have shown the connection as being with the wire 23, while the wire 24 is shown as grounded, or the latter wire may instead be connected with the opposite pole of the motor circuit, in case a return wire instead of the ground return is used in the system. 90

In order for any of the controllers to operate to complete the circuit to the motor, it is necessary that the contactor 17 should be raised, so when the controller handle is moved to its first notch, it completes 10 the magnet circuit through contact 21, wire 20, coil 19, and wire 23, and it is necessary merely to bridge the gap between wires 23 and 24 to further complete the circuit to the opposite pole of the power circuit. To close 10 this gap between the wires 23 and 24, we provide wiring 25 and 26 connected respectively to the wires 23 and 24 which are electrically connected and disconnected by switches 27 and 28 located respectively ad- 11

jacent the controllers 15 and 16 within easy reach of the motorman. Thus, whenever the motorman desires to render the coil 19 operative to actuate the contactor upon the operation of the controller, he closes the switch 27 or the switch 28. Now, the wires 23 and 24 which as has been previously explained run the length of the car, may be coupled by flexible connectors 29, to the wires 23^a and 24^a of an adjacent car. In case the car 10 is disabled and is to be driven by the car 11 from behind, it is merely necessary to open the switch 28 of the disabled car and the switches 27^a and 28^a of the driving car, corresponding respectively to switches 27 and 28 of the disabled car. The motorman standing on the platform 13 of the disabled car will thus by opening and closing the switch 27 control the motor circuit of the driving car, as will be obvious when it is borne in mind that the driving car has connections and wiring similar to that described for the disabled car 10, and thus the control of the circuit between wires 23^a and 24^a from the disabled car operates the contactor 17^a of the driving car.

It will be necessary, of course, for the motorman of the car 11 to stand upon the platform 12 and to operate his controller 15^a, but this controller 15^a is rendered operative or inoperative at will by the motorman of the disabled car standing on the platform 13 operating the switch 27. When the conductor signals to go ahead, the motorman of the disabled car closes the switch 27 whereupon the motorman of the driving car operates his controller to bring the motor up to speed. Whenever the motorman of the disabled car finds it necessary for any reason to stop the cars, he opens the switch 27 and the circuit is immediately opened by the contactor. The motorman on the rear car immediately throws his controller to off-position and does not turn it on again until the conductor has given his signal to go ahead or he finds that his circuit has been rendered operative by the forward motorman which he can find by moving his controller to the first notch.

It will be clear, of course, that the wiring on the car 11 is exactly the same. In addition to controlling the motor circuit of the driving car, it is desirable for the motorman of the disabled car to apply his own brakes. For this purpose, the air tank 30 of each car is provided with pipes 31 running the length of the car which may be coupled to each other by the flexible pipe coupling 32. The valves 33 in the pipes 31 may be opened whenever the two sets of pipes 31 of two cars are coupled together. In this way, the air pressure from the tank 30 of the rear car is admitted into the tank 30 of the forward car and the brakes on the forward car could then be operated by the pressure thus se-

cured. The air compressor on the rear car may have to do double duty in this case, but it is capable of performing this in emergencies.

It will be readily seen that the motorman of the disabled car may control any number of cars in the same manner above described which are coupled together by the connections above described. Thus, in case a car should be disabled before a steep grade, two cars can be utilized in pushing the disabled car up the grade and all the three cars may be controlled by the motorman on the front platform of the disabled car. Furthermore, if it is desired at times to run several cars in train, our improved system will make it possible for the front motorman to control the train with the assistance of the motorman on the individual cars.

Having thus described our invention, we claim as new and desire to secure by Letters Patent:

1. In a car control system, the combination with a motor circuit, a manually operated controller, a contactor for making and breaking the motor circuit, actuating means for the contactor, means for connecting said actuating means with a car in advance of the first car, and means on the forward car for setting the actuating means into operative and inoperative relation.

2. In a car control system, the combination with the motor circuit of a car, a controller therefor, a contactor in series therewith, an electro-magnet for actuating the contactor, wiring from said electro-magnet to a source of current, a forward car in advance of the first mentioned or rear car, wiring in said forward car which may be coupled to connectors running from the wiring of the magnet, and means for opening and closing the circuit in the wiring of the forward car by the motorman of the forward car, whereby the magnet for the contactor on the rear car is set into operative and inoperative position by the motorman of the forward car.

3. In a car control system, the combination with a motor circuit, a controller, a contactor in series with the controller, an electro-magnet for operating the contactor, wiring for connecting said magnet with a source of current, wiring running to the front and rear platforms of the car for completing the magnet circuit independently of the controller, switches in said last mentioned wiring, said switches being located in a convenient position for the motorman on the front and rear platforms, connections from the magnet circuit adapted to be coupled to an adjoining car, wiring on said adjoining car connected to the first car by the coupling, and a switch in the last mentioned wiring located at the front platform of the last mentioned or forward car where-

by the motorman on the forward car may control the operation of the magnet of the rear car.

4. In a car control system, the combination with a motor circuit, a controller, a contactor in series with the controller, an electro-magnet for operating the contactor, wiring for connecting said magnet with a source of current, wiring running to the front and rear platforms of the car for completing the magnet circuit independently of the controller, switches in said last mentioned wiring, said switches being located in a convenient position for the motorman on the front and rear platforms, connections from the magnet circuit adapted to be coupled to an adjoining car, a forward or disabled car, wiring on said forward car independent of the controller thereof connected to the coupling of the rear car, and a switch in the last mentioned wiring disposed on the forward platform of the forward car whereby the motorman on the forward car controls the operation of the contactor in the motor circuit of the rear car.

5. In a car control system, the combination with a motor circuit, means located on

the car whereby the motorman controls the circuit from the platform of the car, and means associated with the control circuit for connecting with a forward car, and means associated with the connection to the forward car whereby the controller on the rear car is rendered operative or inoperative by the motorman on the forward car.

35

6. In a car control system, the combination with a motor circuit, means located on the car whereby the motorman controls the circuit from the platform of the car, means associated with the control circuit for connecting with a forward car, and means associated with the connection to the forward car whereby the controller on the rear car is rendered operative or inoperative by the motorman from either end of the forward car.
